UNITED STATES PATENT OFFICE.

AUGUST H. HAGEMEIER, OF ST. LOUIS, MISSOURI, ASSIGNOR TO ST. LOUIS CAR COMPANY, OF SAME PLACE.

DESIGN FOR A TRUCK-BOLSTER.

SPECIFICATION forming part of Design No. 34,292, dated March 26, 1901.

Application filed February 27, 1901. Serial No. 49,174. Term of patent 14 years.

To all whom it may concern:

Be it known that I, AUGUST H. HAGEMEIER, a citizen of the United States, residing at St. Louis, in the State of Missouri, have invented and produced a new and original Design for Truck-Bolsters, of which the following is a full, clear, and exact description, reference being had to the accompanying drawings, forming part of this specification.

Figure I is a perspective view of a truck-bolster, showing my new design. Fig. II is a vertical section of the bolster.

As shown in the drawings, the leading or material feature of my design consists of a horizontal body portion 1, at the sides of which

are vertical flanges 2. At the ends of the body portion are flat surfaces 3, beyond which are downwardly-extending inclined portions 4, at the lower ends of which are horizontal portions 5. Projecting beneath the horizontal portions 5 are extensions 6. In the center of the body portion is a circular portion 7.

I claim as my invention—

The design for a truck-bolster herein shown and described.

AUGUST H. HAGEMEIER.

In presence of—

MORITZ WEBER,
LOUIS RUBENBAUER.
